BENJAMIN B. ENGLANDER, OF NEW YORK, N. Y., ASSIGNOR TO ENGLANDER SPRING BED COMPANY, OF BROOKLYN, NEW YORK, A CORPORATION OF NEW YORK.

CONVERTIBLE BED AND DIVAN.

1,061,956.

Specification of Letters Patent. Patented May 13, 1913.

Application filed September 16, 1912. Serial No. 720,474.

To all whom it may concern:

Be it known that I, BENJAMIN B. ENGLANDER, a citizen of the United States, residing at New York, borough of Manhattan, in the county of New York and State of New York, have invented certain new and useful Improvements in Convertible Beds and Divans, of which the following is a specification.

10 This invention relates to convertible beds and divans, herein designated as divanettes, the object of the invention being to provide an improved convertible divanette simple in its construction and operation and which 15 can be readily opened without withdrawing the same from the wall against which it may be placed, and in which pedally operated means are used for shifting the heaviest part of the structure, whereby it may be 20 readily operated by a woman with comparatively little effort.

In apartments, flats and small rooms where it is necessary to economize space the usual six-foot length convertible couch or 25 bed frequently requires too much room lengthwise of the structure, so that the object of the present improvement is to provide a compact convertible structure which will take up but four feet lengthwise there- 30 of,—in other words, will be about as long as the ordinary double bed or couch when opened up is wide and yet can be transformed into a double bed having the usual length of such a structure, to wit about six 35 feet, thereby making a highly desirable article of furniture by reason of the fact that when closed to form the divan it takes up but about four feet lengthwise and but about two feet crosswise thereof, while it can be 40 opened up from the front to form a six-foot length bed without the necessity of moving the structure from the wall and by the expenditure of very little effort, so that the structure as a whole, when in the form 45 of a divan, can be placed in a space of about two by 4 feet and have an ornamental appearance and be a comfortable article of furniture with a seat and back, and can be drawn out, when it is desired to transform 50 it into a bed, toward the center of the room, which is usually unoccupied by furniture, to form a full six-foot length bed which will be entirely comfortable to sleep upon.

In the drawings accompanying and forming part of this specification, Figure 1 is

an end view of this improved divanette when in the form of a divan; Fig. 2 is an end view thereof partly transformed into a bed; Fig. 3 is likewise an end view thereof illustrating the structure transformed into a six-foot length bed; and Fig. 4 is a detail front view of one end of the swinging section illustrating the sides or arms thereof in their upright positions and by dotted lines in their folded positions.

Similar characters of reference indicate corresponding parts throughout the figures of the drawings.

The present improvement comprises what may be designated as a stationary or seat 70 and back supporting section 2, a sliding or middle section 3 sliding over the stationary or back supporting section 2, a swinging front or seat section 4 and a rear or back swinging section 15. The stationary section 75 consists of a pair of end frames 5, each comprising a transverse or cross member 6 having supporting means or legs 7. These end frames are connected by suitable longitudinally extending members or side bars and 80 braces. This section rests upon the floor and is not ordinarily movable and therefore need not be provided with casters, and it forms a frame work over which the sliding or middle section 3 and the front or swing- 85 ing section 4 rest when in the form of a divan and from the top of which the sliding or middle section and the front or seat section are shifted when the structure is transformed into a bed, and in which position it forms the support for the back sec- 90 tion.

The sliding or middle section 3 is somewhat similarly formed, and consists of a pair of end frames 9, each consisting of a transverse or cross members 10 and legs 11, and which end frames are suitably connected by lengthwise extending members or side bars 12 and braces 13. Stretched between the end frames of the sliding or middle section is a suitable spring 14, which may be of any desired form.

Hinged to the sliding or middle section 3, at the rear thereof, is the back section 15, comprising a frame made up of a pair of end members or bars 16 connected at their outer ends by a longitudinally extending bar and preferably adjacent to their inner ends by a drop form of side bar 17. This frame likewise carries a metallic fabric or 116

spring 18 of any suitable construction. In the present instance the fabric forming the seat and that forming the back is made as one continuous structure, whereby there is no break between the back and seat sections, thus providing a much more comfortable spring to sleep upon. The back is hinged to the sliding section by a pair of short links 19, one at each end.

10 The back section is connected to the rear of the stationary section by a pair of links 20, one at each end thereof, these links being pivotally connected to the ends of the back section, while the lower ends of the 15 links are slotted for the reception of headed pins 21 carried by the rear leg of the stationary section, and for facilitating the lowering and raising of the back section suitable coil springs 22 are provided, one at 20 each end, each connected to a link and to the stationary section.

Hinged to the front of the sliding or middle section 3 is the swinging front or seat section 4, likewise comprising a pair of 25 end bars 23 suitably connected at their outer ends by a lengthwise extending bar, the inner ends being hinged by means of short links 24 to the outer ends of the sliding or middle section 3. This swinging section, 30 when the structure is in the form of a divan, rests upon the sliding or middle section, which in turn rests upon the stationary section, so that the divan has a highly resilient seat. Connected to each end of the swinging 35 section is a side or end arm 25, which arm is of an integral structure and forms the end of the structure when in the form of a divan and is of such height that when the swinging front section is swung to the front 40 of the middle section 3 the arms will rest upon the floor and form supports or legs for the swinging front section. In the present instance these end or side arms are connected to upright lugs 26 carried at the 45 end of the swinging front section, and for this purpose each lug is provided with a pair of pins 27 out of alignment, and each end of each arm is flattened and provided with a pair of slots 28 and 29 for the reception of such pins, one of such slots, as 28, being an open ended one, whereby the arms may be folded down under the stuffed mattress when desired, as for instance when the structure is to be shipped or stored away.

50 Carried by the back section 15 and front swinging section 4 when the structure is in the form of a divan, is a three-section stuffed mattress *a*, *b* and *c*, the sections *b* and *c* forming the seat of the divan while the section *a* forms the back. The section *a* is permanently attached in any suitable manner to the back section 15, while the other two may be shifted on to the back when the latter is in a horizontal position as in Fig. 2 55 and from thence on to the middle or sliding

section 3 and the front or swinging section 4 when the structure is in the form of a bed as in Fig. 3.

For shifting the sliding section to convert the structure into a double bed, and to facilitate the change thereof into a divan, pedally operated means is provided, and this in the present instance comprises a rock shaft 29 extending from end to end of the stationary section and supported by the forward legs thereof. Connected to the ends of this rock shaft are a pair of crank arms 30 to which is pivotally connected at each end of the structure a lever 31, which is also pivotally connected to the rear leg of the sliding section, as at 32, by means of a headed pivot 33 projecting into a slot 34 carried by the leg of the sliding section. By operating either of these pedal levers the sliding section and its swinging seat section will be shifted forward together from off the top of the stationary section to the front thereof, and simultaneously the back will be carried forward with the sliding section and lowered to rest upon the stationary section, whereupon the two parts *b* and *c* of the stuffed mattress may be thrown over upon the back part *a* and thereupon the swinging section may be swung from off the top of the sliding section and on to the floor to form a full length double bed. Then the two stuffed sections *c* and *b* of the mattress may be swung over upon the sliding and swinging sections respectively in the manner shown in Fig. 3, in readiness for use.

To transform the structure into a divan, it is merely necessary to reverse this operation, by throwing the sections *b* and *c* of the stuffed mattress into the position shown in Fig. 2, then swinging the swinging front or seat section back on to the sliding section and thereupon throwing the stuffed sections *b* and *c* on to the seat section and operating the pedal, whereupon the back will be raised and the seat sections returned to their position over the stationary section in the manner shown in Fig. 1. Thus it will be observed that the heaviest part of the structure, comprising the middle or sliding section 3 and the swinging front section 4, together with the two sections of the stuffed mattress thereon and the back and its section of stuffed mattress, may all be operated by means of either pedal without the necessity of a woman bending down and manipulating these structures by hands, so that only a comparatively small part of the structure, to wit the sections *b* and *c* of the stuffed mattress and the swinging front section 4, without the stuffed mattress attached thereto, need be manipulated by the hand, and as these are light in weight compared with the entire structure it follows that the divanette may be 130

readily handled with comparatively little effort. It will also be observed that the stationary section supports the sliding and swinging front sections when in the form of a divan and also forms the support for the back section, which is carried forward and downward onto said stationary section without the necessity of moving the same from the wall when the structure is in the form of a double bed. It will also be observed that the swinging back section and the swinging front section are both connected to the sliding or middle section and move therewith when the structure is transformed into a double bed to carry the back forward and downward to rest upon the stationary section and to carry the front or swinging section into position to be swung from the top of the sliding section to the front thereof.

I claim as my invention:

1. A divanette comprising a stationary section, a sliding section, a front section hinged to said sliding section, and a back section hinged to said sliding section and adapted to rest upon the stationary section when the sliding and front sections are shifted forward of the stationary section.

2. A divanette comprising a stationary section, a sliding section, a front section hinged to said sliding section, and a back section hinged to said sliding section and adapted to rest upon the stationary section when the sliding and front sections are shifted forward of the stationary section, said front section resting on top of the sliding section and the latter on top of the stationary section when the structure is in the form of a divan.

3. A divanette comprising a stationary section, a sliding section, a front section hinged to said sliding section, a back section hinged to said sliding section and adapted to rest upon the stationary section when the sliding and front sections are shifted forward of the stationary section, said front section resting on top of the sliding section and the latter on top of the stationary section when the structure is in the form of a divan, and means for simultaneously shifting the back section down or up and the sliding section and front hinged sections forward or backward from off of or on to the stationary section.

4. A divanette comprising a shiftable section, a back section hinged thereto at one side, a front section hinged thereto at the opposite side and all simultaneously movable together to transform the structure into a bed or a divan, means for supporting the back section, and means for shifting said sections.

5. A divanette comprising a shiftable section, a back section hinged thereto at one side, a front section hinged thereto at the

opposite side and all simultaneously movable together to transform the structure into a bed or a divan, and means stationary during the movement of said sections for supporting the back section.

6. A divanette comprising a shiftable section, a back section hinged thereto at one side, a front section hinged thereto at the opposite side and all simultaneously movable together to transform the structure into a bed or a divan, and means stationary during the movement of said sections for supporting the back section and in position when the structure is in the form of a divan to support the sliding and front hinged sections.

7. A divanette comprising a sliding section, a back section hinged thereto at one side for movement therewith into a raised or lowered position, a front section hinged to said sliding section at the opposite side thereof and forming with said sliding section the seat of the structure in one position and in another position a section of the bed, and means for supporting the back section when in its lowered position, said hinged front section having means for supporting it when in position to form a part of the bed.

8. A divanette comprising a sliding section, a back section hinged thereto at one side for movement therewith into a raised or lowered position, a front section hinged to said sliding section at the opposite side thereof and forming with said sliding section the seat of the structure in one position and in another position a section of the bed, and means for supporting the back section when in its lowered position, said hinged front section having means for supporting it when in position to form a part of the bed, said means forming the arms when the structure is in the form of a divan.

9. A divanette comprising a sliding section, a back section hinged thereto at one side for movement therewith into a raised or lowered position, a front section hinged to said sliding section at the opposite side thereof and forming with said sliding section the seat of the structure in one position and in another position a section of the bed, and means for supporting the back section when in its lowered position, said hinged front section having means for supporting it when in position to form a part of the bed, said means forming the arms when the structure is in the form of a divan, said arms having a hinge connection whereby they may be folded on to the hinged section.

10. A divanette comprising a sliding section, a back section hinged thereto, a front section hinged thereto and resting flatwise thereof upon the sliding section to form a divan, means for sliding said sliding section and front section together and raising or lowering the back section, means for sup-

- porting the back section, and means carried by the front section and forming arms therefor when the structure is in the form of a divan and supporting means therefor when the structure is in the form of a bed.
11. A divanette comprising a sliding section, a back section hinged thereto, a front section hinged thereto and resting flatwise thereof upon the sliding section to form a divan, means for sliding said sliding section and front section together and raising or lowering the back section, means for supporting the back section, and means carried by the front section and forming arms therefor when the structure is in the form of a divan and supporting means therefor when the structure is in the form of a bed, said arms foldably connected with said front section.
12. A convertible divanette comprising a stationary bed section, a sliding bed section shiftable thereover, a swinging back section hinged to the sliding section, and a front section also hinged to the sliding section, all of said movable sections shiftable simultaneously, a pair thereof to the front of said stationary section and one thereof on to said stationary section to form a double bed.
13. A convertible divanette comprising a stationary bed section, a sliding bed section shiftable thereover, a swinging back section hinged to the sliding section, a front section also hinged to the sliding section, all of said movable sections shiftable simultaneously a pair thereof to the front of said stationary section and one thereof on to said stationary section to form a double bed, and pedally operated means for shifting said sections.
14. A divanette comprising a sliding section, a front section hinged thereto, a back section hinged thereto, means linked to said back section for supporting it, and means connected to the front section and in one position forming the arms thereof and in another position supporting means therefor.
15. A divanette comprising a sliding section, a front section hinged thereto, a back section hinged thereto, means linked to said back section for supporting it, and foldable means connected to the front section and in one position forming the arms thereof and in another position supporting means therefor.
16. A divanette comprising a sliding section, a front section hinged thereto, a back section hinged thereto, means linked to said back section for supporting it, means connected to said supporting means and to said sliding section for shifting the latter and therewith the front section, and means connected to the front section and in one position forming the arms thereof and in another position supporting means therefor.
17. A divanette comprising a stationary section or frame, a sliding section movable relatively thereto, a back hinged to said sliding section and supported in its lowered position by said stationary section, a reversible section also hinged to said sliding section, and means for supporting it.

Signed at Brooklyn, N. Y., this 14th day of September, 1912.
